UNITED STATES PATENT OFFICE.

FRANK A. LUNDQUIST, OF CHICAGO, ILLINOIS, ASSIGNOR, BY MESNE ASSIGNMENTS, TO WESTERN ELECTRIC COMPANY, INCORPORATED, A CORPORATION OF NEW YORK.

TELEPHONE EXCHANGE.

Application filed August 5, 1904. Serial No. 219,603.

To all whom it may concern:

Be it known that I, FRANK A. LUNDQUIST, a citizen of the United States of America, and a resident of Chicago, county 5 of Cook, and State of Illinois, have invented certain new and useful Improvements in Telephone Exchanges, of which the following is a specification.

My invention relates to telephone exchanges, and more particularly to the arrangement of central office devices for automatically connecting together two subscribers when the total number of subscribers rises to large numbers. The object 10 of the present invention is an extension and an elaboration of the system set forth in my Patent No. 747,197, issued Dec. 15, 1903, in my Patent No. 776,524, issued December 6, 1904, and my Patent No. 1,369,288, issued 15 February 22, 1921. The said application is very similar to Patent No. 776,524 but has its auxiliary switches interconnected by groups, as will hereinafter be explained.

In an exchange system made according to 20 the present invention there are three kinds of switching mechanisms which I designate as main switches, auxiliary switches, and intermediate switches. These three kinds of switches do not need to be of any particular construction but each performs certain functions peculiar to itself.

As the details of construction of these switching mechanisms do not form a part of the present application they are shown in 25 the drawings only in diagrammatic form. I will say, however, that it is not essential to the operation of an exchange of this character that the switches used should embody mechanical construction of an unknown kind. In giving a general description of the switching mechanisms, I will therefore assume that each mechanical operation set forth is performed in the simplest possible manner.

40 In the accompanying drawings,

Figs. 1, 2, and 3, taken together, show two switches of each kind and form a diagram showing how they are connected together.

45 Figs. 4, 5, 6 and 7, taken together form a general diagram showing the arrangement

for an exchange for ten thousand subscribers, said diagram being abridged with 2 instead of 10 taken as a basis.

Fig. 8 is an elevation of one of the main switches;

55 Fig. 9 is a section on line 9—9 of Fig. 8;

Fig. 10 is a section on line 10—10 of Fig. 8;

Fig. 11 is a somewhat enlarged section, 60 on line 11—11 of Fig. 8, of the springs operated by magnet C.

Fig. 12 is an elevation of one of the auxiliary switches; and

Fig. 13 is a rear view of some contacts located on the back of the auxiliary switch frame.

65 In arranging a 10,000 subscriber exchange of this kind, there is a main switch for each subscriber. These switches are divided into primary groups of 100, and secondary groups of 1,000, each secondary group consisting of ten primary groups. In case there were more than 10,000 subscribers, and up to 100,000 subscribers, then there would be tertiary groups each made up of a number of secondary groups. This is on 70 the assumption that 10, the basis of our system of notation, is also the basis on which the grouping is made. Any other number might be taken as the basis. These main switches are shown in Fig. 1 and in the lower part of the general diagram. The 75 whole number of main switches may be called a "set."

80 The auxiliary switches are shown in Fig. 3 and in the upper part of the general diagram. They are normally taken as ten per cent in number of the main switches, and are divided into corresponding groups. That is, there are 10 auxiliary switches in each primary group, 100 in each secondary group, and 1000 in each tertiary group when such groups are used. The first primary group of auxiliary switches as used for making connections to the different switches in the first primary group of main switches. 85 In like manner the second group of auxiliary switches is for connections to the second group of main switches, and so on. The whole number of auxiliary switches 90 may also be called a set.

5

65

70

75

80

85

90

95

100

The intermediate switches are shown in Fig. 2 and in the central part of the general diagram. Normally they are equal in number to the auxiliary switches and are divided 5 into the same number of groups. They serve as intermediates in making connections from any main switch to any desired primary group of auxiliary switches. There are one or more sets of these intermediate switches according to the number of main switches in the 10 exchange. Thus, when there are from 1,000 to 10,000 main switches there is one set of intermediate switches. When there are from 10,000 to 100,000 main switches there are 15 two sets of intermediate switches.

The present application shows only one set of such intermediate switches, though it will be readily understood that a second set might be inserted between the present set 20 and the auxiliary switches. Such second set would be made up of intermediate switches precisely like the first set and differing in the same way from both the main and auxiliary switches.

Referring to Figs. 4 to 7, each sheet represents a primary group of main, intermediate and auxiliary switches. The switches on Figs. 4 and 5 taken together represent a secondary group of each kind, 30 and Figs. 6 and 7 represent another secondary group of each kind.

The first primary group of intermediate switches is adapted to receive connections from any one of the 1,000 main switches in 35 the first secondary group, and to extend those connections to the first secondary group of auxiliary switches. The second primary group of intermediate switches receives connections from the same main 40 switches but extends them to the second secondary group of auxiliary switches, and so on.

This matter may be stated in another way. The intermediate switches in any secondary group are arranged to receive connections 45 from any main switch in the corresponding secondary group of main switches. Assuming any secondary group of intermediate switches, any switch in the first primary group of such secondary group can extend a received connection to one of the switches in the first secondary group of auxiliary switches. The second primary group of intermediate switches can extend connections 55 to some switch in the second secondary group of auxiliary switches.

Instead of the first primary group of intermediate switches extending the connections to the first secondary group of auxiliary switches, and the second primary group of intermediates extending to the second secondary group of auxiliaries; the first primary group of intermediate switches may extend the connection to the first primary

group of each secondary group of auxiliary switches, and the second primary group of intermediates may extend to the second primary group of each secondary group of auxiliary switches. This difference is a mere detail that involves nothing more than 70 precedence in the order of selecting primary or secondary groups of main switches.

In operation the subscriber operates his connected main switch so as to make a preliminary selection of a desired primary group of intermediate switches. As his main switch can reach only the 100 switches in the corresponding group of intermediate switches, his preliminary selection is of a definite group of ten switches. He then starts his main switch into automatic operation causing it to move into successive connection with the different switches of this preliminarily selected group. As soon as the main switch reaches connection to an intermediate switch which is not in use and which is consequently in its normal position, his main switch automatically stops and the selected intermediate switch is automatically moved away from its normal position. The selected intermediate switch is thereby transferred from the unemployed to the employed class and cannot be reached by any other main switch until after it has been returned to its normal position. 80

If the subscriber's preliminary selection just described had been for the second primary group of the associated secondary group, then the finally selected intermediate could connect to any switch in the second group of auxiliary switches. 95

The subscriber then operates the selected intermediate switch so as to make a preliminary selection of a desired primary group of auxiliary switches, and starts the intermediate switch into automatic operation. In the same manner as previously described, the intermediate selects an idle auxiliary switch and removes it to the employed class. The selected auxiliary switch may then be moved to connection with any one of the main switches that are located in the corresponding primary group. 105

The main switches best adapted for exchanges of the kind here described each have two groups of contact points. Each group has 100 contact points arranged in ten rows of ten points each. Corresponding contact points in the two groups I call a pair of contact points. Thus, the first contact point of the first row of one group, and the first contact point of the first row of the other group constitute a pair. 115

There is a contact maker, usually called a "wiper" for each group of contact points. These wipers are mounted upon a carriage, but insulated from each other, and the carriage is movable laterally so as to bring the 125

wipers adjacent to successive rows of contact points. The carriage is also movable vertically so as to carry the wipers over the rows of contact points which are adjacent to them at the time of beginning the vertical movement.

Each switch is provided with a series of magnets for performing the mechanical operations and for closing contacts as will be 10 hereinafter described. In the drawings, those magnets which have mechanical work to perform are shown of relatively large size, while those which simply close contacts are shown of relatively small size. 15 Thus the magnet A is the one used for moving the wipers laterally while the magnet a is simply a relay for closing the connections for A. In the same way, B is the magnet for moving the wipers vertically while b is a relay for B. As the mechanical connections for causing such movements do not necessarily involve any special or unknown constructions they are not shown, but are assumed to be made in any of the 20 simple and well known ways.

The magnet B has its armature arranged so as to make and break its own electrical connections. A construction for this is shown, though any other convenient form 30 might be used.

A magnet C has a hook c connected to its armature lever, which hook catches over a contact spring when the armature is attracted and which makes and breaks a series 35 of electrical connections when the armature is released. A spring connected to the armature lever furnishes the power for operating these electrical connections. Although this magnet is a contact closing magnet it has some work to perform and is consequently 40 shown of intermediate size.

There is also a magnet J used to release the carriage that carries the wipers from its propelling magnets A and B so that the 45 said wipers may fall back to their normal position. The mechanical connections for this may be of any of the well known forms.

The carriage has a projection upon it 50 which, when at its lowest position, opens connection between springs 32 and 33. Also on the carriage is a contact maker 16 which is normally disconnected from a contact strip 15, but makes connection therewith 55 upon the first lateral movement, which connection is broken upon the first upward movement. In falling back to its normal position, the carriage strikes a tail upon the hook c and releases it after it has been operated by the magnet C. For convenience, I have marked by the character M detached 60 portions of the carriage that effect such mechanical operations. There are also certain other contacts made and broken by the 65 movements of the carriage which will be

readily understood by an inspection of the drawings and will be further explained hereinafter.

The description so far relates to certain elements that form a part of whatever kind of main switch is used in an exchange of this character. Provided these elements perform the functions set forth they may be of any mechanical construction that is simplest or most convenient.

A main switch suitable for use in this kind of an exchange is shown in Figs. 8 to 11. In these views 300 is a vertical metallic frame to which are secured the parts forming the switch mechanism. Near the upper part of this frame is a block of insulation 301 which carries the two groups of contact points and also the contact strips 15, 158, 165 and 166. On the frame 300 are lugs 302 which carry the parallel rods 303, and on these rods is the vertically movable carriage M. Secured to the slide M is a ratchet bar M¹ suitably guided by a slot M² in said bar and a pin 304 in the frame 300. Magnet B operating through its armature 305 and pawl 306 serves to move the carriage M upward step by step. A holding pawl 307 prevents a return of the carriage to normal position until released. In normal position of the switch a hook on the armature 305 engages a hook on the pawl 307 and holds that pawl from engagement with the ratchet M¹, but upon the first operation of the magnet B these hooks are disengaged and the pawl 307 engages the ratchet M¹.

Secured to the armature of the release magnet J is a hook 308 which extends adjacent to a projection on the pawl 307. If the magnet J is actuated after the carriage has been advanced and the pawl 307 is in engagement with the ratchet M¹, the hook 308 will engage the projection of said pawl. Upon breaking the circuit for an actuating impulse through the magnet J, the return of the armature and the connected hook 308 serves to release the pawl 307 from the ratchet M¹ and also to throw the hook on said pawl behind the hook on the armature lever 305 of magnet B.

This permits the ratchet M¹ and carriage M to fall by gravity to their lowest or normal position, which lowest position is determined by the lower lugs 302 on the frame 300.

In the carriage M is a slide M⁵ which carries the insulated wipers or contact makers 16, 43 and 69, and also mounted on suitable posts on this slide is a ratchet bar M⁶.

At a suitable position on the frame 300 is a magnet A whose armature lever 309 carries a pawl 310 adapted to engage the ratchet M⁶ to move the slide M⁵ laterally each time the magnet A is actuated. A holding pawl 311 pivoted on the carriage M serves to prevent backward movement of the slide M⁵.

When the mechanism is in its normal position this pawl 311 is out of engagement with the ratchet M^6 by reason of its heavy tail end resting upon the end of a spring 312 which is supported on the frame.

Secured on the lever 309 is a rod 313, the other end of which carries a collar adapted to engage the spring 312. When the magnet A is actuated to advance the slide M^5 , 10 the collar on the rod 313 strikes the spring 312 and pushes it from under the pawl 311. When the carriage has been moved upward one step, the pawl 311 is lifted far enough for the spring 312 to come again 15 under the tail of pawl 311 so that a dropping of the carriage results in releasing the holding pawl 311. A coil spring 314 which runs over a roll 315 and has one end secured to the frame 300 and the other end to a post 20 on the slide M^5 , serves to return the slide to its normal position when released. The other elements of the main switches will be apparent from inspection of the drawings and from the further description connected 25 with the operation.

The intermediate switches are very largely made up of the same elements, though they have more connections at some places and less at others. They will be readily understood by comparing them with the foregoing description and what appears herein-after. The magnets A^1 , B^1 , etc., of the intermediate switches correspond to the magnets A, B, etc. of the main switches.

35 The auxiliary switches have a good many of the characteristics of the main switches but differ therefrom in many other respects. Each one has three groups of contact points and each group has a corresponding wiper. 40 These wipers are correspondingly moved by means of the corresponding magnets A^2 and B^2 . There are also four other wipers mounted upon a shaft but insulated from each other. Magnets E and F operate this 45 shaft through a ratchet wheel as shown and as will be hereinafter described, and cause these wipers to be moved over contact points. Other features of the auxiliary switches will be set forth in connection with the operation.

50 The auxiliary switch is illustrated in Figs. 12 and 13, and in many respects is like the main switch. For convenience, those parts of the mechanism which are substantially the same are given the same reference characters. The parts operated by the magnets A^2 , B^2 and J^2 are in all essentials the same as those described in connection with magnets A, B and J of the main switch and need no further description.

60 On a spindle N is a ratchet wheel N^1 having teeth cut only on a portion of its periphery. When the magnet E attracts its armature 315 the pawl 316 releases the holding pawl 318 from catch on lever 322, and engages a tooth in the wheel N^1 .

When the magnet releases its armature the spring 317 causes the pawl 316 to move the wheel one step. The holding pawl engages the first adjacent notch and holds the wheel from returning until released. The magnet 70 E can advance the wheel only three steps because there are only three adjacent notches in the wheel. As there are only three notches adjacent to the holding pawl 318, that pawl can hold for only three steps. At 75 the end of three steps another notch 319 is adjacent to a pawl 320 on the armature 321 of the magnet F. In this position an actuation of the magnet F serves to advance the wheel N^1 another step, but as the holding pawl 318 does not operate beyond three steps a release of the armature 321 permits the wheel N^1 to return to the three-step position.

On the lower end of the ratchet bar M^1 is 85 pivoted a bell-crank lever 322, one arm of which is on one side of the bar and the other arm of which is on the other side.

The vertical arm of the lever 322 has a hook on its end which is adapted to engage a 90 tail on the holding pawl 318 and release that pawl from the wheel N^1 when the carriage of the auxiliary switch returns to its normal position.

A spring shown in dotted lines under the wheel N^1 of Fig. 12 serves to return the wheel N^1 and its spindle N to normal position. The spindle N runs through the frame of the machine and on its other end carries four insulated contact makers 97, 114, 126 100 and 141.

Adjacent to these contact makers are insulated contact points arranged as shown in Fig. 13, which figure shows the contact makers in normal position. When the ratchet wheel N^1 is advanced step by step as previously described, the contact makers are advanced step by step over their adjacent contact points.

In its normal position the lower end of the bar M^1 engages a pin on a pawl or catch 324 and holds said catch clear of the armature lever 323 of the magnet L.

When the carriage moves upward one step the catch drops into a position suitable for engaging and holding the lever 323 in its moved position when actuated by the magnet L.

When the carriage again drops to its normal position, it releases the catch 324 and permits armature 323 to return to its normal position. The armature 323 controls certain contact springs as will be hereinafter described.

In arranging an exchange all of the main switches located in one secondary group are connected to a bank of wires, there being as many wires in a bank as there are contact points on one switch. Ordinarily there are 120 100 pairs of contact points on a switch and 125 130

hence there would be 100 pairs of wires in the bank and 100 intermediate switches connected to the bank. In some cases, it is desirable to have more than 100 intermediate switches to 1000 main switches, in which event the main switches will have more than 100 pairs of contact points. In a case of this kind the extra number of contact points is obtained by lengthening the vertical rows of contact points and not by increasing the number of rows. This is because the upward movement of a switch is an automatic operation and is wholly independent of our system of notation.

Each other one of the secondary groups of main switches is likewise connected to a bank of wires, and these wires in turn are connected to a corresponding group of other intermediate switches. As thus arranged, each secondary group of main switches forms a unit that is not directly connected in any way with any of the other secondary groups. To make connection from one of these units to another, it is necessary to go through some one switch in the set of auxiliary switches. It will be observed that there are as many banks of wires as there are secondary groups of main switches and that each group, as a body, is connected to a corresponding bank of wires.

There are as many secondary groups of intermediate switches as there are secondary groups of main switches, and these secondary groups of intermediate switches are connected to an equal number of banks of wires. These last connections are not, however, from a secondary group as a whole to a bank as a whole as is the case with the main switches. Considering each secondary group of intermediate switches as a unit, the first primary group of each unit has its contact points connected to the first bank, the second group of each unit has its contact points connected to the second bank, and so on. As before stated, the ordinary number of intermediate switches in a primary group is 10, and the number in a secondary group is 100. When the number of intermediate switches is increased, this increase is obtained by adding switches to the primary groups and not by increasing the number of either the primary or secondary groups.

When the main switches have their vertical rows of contact points lengthened so that the number of intermediate switches in each primary group may be increased, the intermediate switches also usually have their vertical rows of contact points correspondingly lengthened so that the number of auxiliary switches in each primary group may also be increased. The object of this increase in the number of switches in the primary groups of intermediate and auxiliary switches is to increase the certainty of

the automatic upward movement of a main switch or an intermediate switch finding an unemployed switch to which it can connect.

Returning now to the several banks of wires which are connected to the contact points of the intermediate switches, that bank which is connected to the first primary group of each unit of intermediate switches is connected in turn to the first secondary group of auxiliary switches. That bank which is connected to the second primary group of each unit of intermediate switches is connected to the second group of auxiliary switches, and so on.

All of the contact points in the first primary group of auxiliary switches are connected to a bank of wires that are in turn connected to the first primary group of main switches. In like manner, each other primary group of auxiliary switches has its own bank of wires which are connected in turn to the corresponding primary group of main switches.

In addition to this, each primary group of auxiliary switches has a special bank of wires of its own, which special bank serves as means for interconnecting the third groups of contact points on these switches. These interconnections serve as a means for preventing interfering connections as will be hereinafter described.

In an exchange of the present character, there is a battery X, a generator G, a "busy buzz" or interrupter W, some condensers in certain lines, and contacts and connections as shown. These various elements are connected up in the manner illustrated. For each main switch there is a telephone station T provided with two contact buttons marked 1st and 2nd.

Referring to the diagram of Figs. 1, 2 and 3, it will be assumed that the subscriber located at the telephone shown at the left of Fig. 1 wishes to talk to the one located at the telephone shown at the right of the same figure. It will also be assumed that the calling station is No. 1 and that the called station is No. 2, 112. In a system of this kind the figures that go to make up the number of a station are themselves used to indicate how the subscriber is to operate in calling any other subscriber. Thus, "2" means that two contacts are to be made, "3" that three contacts are to be made, and so on. In this system also, there is one contact to be made by a different contact making device between the times of making the contacts indicated by each figure. Ordinarily a calling device is located at each station and so arranged that it will automatically make this intermediate contact, the consequence being that the subscriber does not have to regard it and is unconscious of its existence. As such a calling device is not a part of the present application, keys or

contact buttons, as before mentioned, are used.

As the first figure of the number to be called is "2" the subscriber pushes his key 5 or button marked "1st," two times. At the first contact a current flows:—X—1—1^a—2— of calling station—*a*—3—4—T—ground—X. This operates magnet *a* and causes its armature 5, to make connection to contact spring 10 6 when a current flows:—X—1—1^a—2—5—6—7—A—8—9—10—11—12^a—12—13—X—

This operation of the magnet *A* moves the carriage carrying the wipers 43 and 69 laterally one step under the first row of 15 contact points and causes contact maker 16, on a part of the carriage *M*, to engage strip 15 preliminary to an upward movement. As the subscriber presses the button twice this operation is repeated and the wipers 20 are moved to a position under the second vertical row of contact points. To avoid confusion of lines, connections are shown only from this second row of contact points to the bank wires though it is to be understood that there are also connections from the other contact points to similar wires in the same bank.

The subscriber then presses the "2nd" key once when a current flows:—X—1—1^a—30 14—15—16—17—18—*b*—19—20—T—ground—X. This causes the armature 23 to connect to the spring 24 when a current flows:—X—1—1^a—21—22—23—24—25—26—27—28—B—29—30—10—11—12^a—12—35 13—X.

This causes the carriage carrying the wipers to move upward one step and carries the contact spring 16 away from the strip 15 so that no subsequent contact made 40 by the "2nd" key can send an impulse through magnet *b* and thereby again close the contact for magnet *B*. This same upward movement carries another part of the carriage *M* away from springs 32 and 33 so 45 that they may come together and close a new circuit for the magnet *B*.

When this occurs a current flows: X—1—1^a—21—31—32—33—34—35—36—37—28—B—29—30—10—11—12^a—12—13—X. 50 This again operates magnet *B* and moves the wipers upward another step.

The armature lever 38 of the magnet *B* has an arm that engages a fork on the pivoted lever 35. When the armature is attracted this arm throws the lever 35 off of the contact point 36 and thus breaks the circuit for *B*. Upon thus breaking the circuit through *B*, the armature 38 returns to its normal position in the ordinary way and 60 again causes 35 to engage 36. This again operates the magnet. It will thus be seen that by this means the magnet *B* continues in operation automatically making and breaking its own circuit.

65 This causes the wipers to move upward

step by step over the selected row of contact points. When the wipers reach connection to a pair of contact points which are connected to an intermediate switch which at the time is in its normal position, then a current flows: X—1—1^a—21—38—39—40—C—41—42—43—selected contact point—44—45—46—47—*b*¹—48—49—50—51—12^b—13—X.

The passing of a current through *C* causes 75 the hook *c* to catch on spring 30 and break the connection between 30, 10 and 9. It also connects 10 to 150, 71 to 72, and 84 to 83.

The breaking of the connection between 80 30 and 10 breaks the circuit for the magnet *B*, and hence stops the upward movement of the carriage with its wipers in connection with the intermediate switch found in its normal position.

The same current flowing through *b*¹ 85 causes 54 to contact with 55 when a current flows:—X—1—1^b—52—53—54—55—56—57—58—59—B¹—60—61—62—63—12^b—12—13—X. The operation of the magnet *B*¹ 90 moves the carriage of the intermediate switch upward one step and carries the part *M* away from the lever 49 so that that lever shifts from contact point 50 to contact point 82. In the case of the intermediate switches, the part of the carriage which 95 separates 75 and 75^a is made long enough so that it requires two upward steps to remove it. The reason for this is that the first step is for isolating the switch and 75 and 76 are required to be in connection 100 during the lateral movement.

The breaking of the connection at 50 cuts the current from the relay *b*¹ and causes a 105 breaking in the circuit for *B*¹ at 54—55. As a consequence of this no other main switch in moving to connection with the bank wire 45 would find this particular intermediate switch in a position in which it could send an impulse through the relay magnet *b*¹.

The next figure in the number of the station desired being "1" the subscriber presses the "1st" key once. Upon making this contact a current flows: X—1—1^b—64—*a*¹—65—66—67—68—69—70—71—72—73—4—T—ground—X. The operation of relay *a*¹ 110 closes 81 to 80 when a current flows:—X—1—1^b—52—53—74—75—76—77—A¹—78—79—80—81—63—12^b—12—13—X. This moves the wipers of the intermediate switch laterally to a position under the first row of contact points. In sending an impulse as above through the relay *a*¹ there is a branch of the same circuit through the relay *a* of the main switch that causes a closure of 5 and 6 for the magnet *A*. But as the magnet *C* had been previously operated the circuit for *A* had been broken at 30, hence this branch is without effect.

The subscriber then presses the "2nd" key once to start an automatic upward 130

movement of the intermediate switch the same as his main switch had done previously. In this case there is one extra idle upward step at the beginning of the movement, 5 the object of which is to be certain that the portion of the carriage M shown connected to the wipers has moved far enough for the connection between 75 and 76 to be opened before a circuit is completed to some idle 10 auxiliary switch.

Upon closing the "2nd" key the current 15 flows: X—1—1^b—52—82—49—48—b¹—47—46—45—44—43—42—83—84—85—20—T—ground—X. This closes the circuit for B¹ as before and causes another upward 20 movement of the carriage. This causes 75 to close to 75^a thus making a circuit for B¹ the same as was made for B of the main switch. As the armature of B¹ is provided 25 with connection similar to those of B, the magnet B¹ makes and breaks its own circuit and moves the carriage of the intermediate switch upward automatically step by step the same as described for the main switch.

25 When the wipers of the moving intermediate switch reach connection to a pair of contact points that are connected to an auxiliary switch which is at the time in its normal position then a current flows: X—1— 30 1^b—52—86—87—88—C¹—89—90—91—92—93—94—95—b²—96—97—98—12^c—12—13—X.

35 The current through C¹ operates that magnet to break the connection between springs 61 and 62, and also to operate the adjacent contact springs the same as described for the main switch. As the springs 61 and 62 are in the circuit for the magnet B¹ it is evident that the operation of C¹ 40 stops the operation of B¹, and consequently stops the upward movement of the carriage of the intermediate switch with its wipers on the contact points which are in the circuit described.

45 The same current through b² closes 101 to 100 when a current flows: X—1—1^c—99—100—101—102—E—98—12^c—12—13—X. The current through E attracts its armature and causes the pawl thereon to engage and 50 turn the ratchet wheel N¹ and the shaft N. This moves all of the wipers on this shaft from their normal position one step forward and consequently breaks the circuit for the relay b² between 97 and the terminal of the line 98. The operation of the ratchet wheel 55 N¹ is shown in Fig. 3, for the convenience of the diagram, as being made by the armature of E while being attracted. In practical operation, however, it is made by the 60 release movement of the armature in Fig. 12, the object being to prevent a premature breaking of the circuit for b². It will be observed that in this case the relay b² does not close connection for the magnet B², but for 65 another magnet E which magnet, as will be

hereinafter described, finally closes connection for B² through another wiper on the shaft N.

The next figure of the desired station being "1" the subscriber presses "1st" key once when a current flows: X—1—1^c—103— 70 a²—104—105—106—107—108—109—110—111—66—67—68—69—70—71—72—73—4—T—ground—X. This closes 118 to 117 when a current flows: X—1—1^c—99—112—113— 75 114—115—A²—116—117—118—119—98—12^c—12—13—X. This moves the wipers to a position under the required rows of contacts. If the figure in the number for the desired station had been greater than "1" 80 then the key would have been pressed a corresponding number of times.

The "2nd" key is then pressed once when a current flows: X—1—1^c—99—112—113— 85 120—97—96—b²—95—94—93—92—91—90—121—122—46—45—44—43—42—83—84—85—20—T—ground—X. This again closes the circuit for the magnet E causing an other advance of the wipers on shaft N. In this position the wiper 114 is on the 90 terminal of the wire leading to magnet B².

The next figure being "2" the subscriber 95 presses "1st" key twice. This closes circuit through a² the same as before. This time the contact between the armature 118 and the spring 117 closes the circuit for B² because of the position of the wiper 114 and the current is the same as previously described for A² except for the substituted link between 114 and 116. This being repeated 100 carries the wipers on the carriage upward to the desired pair of contact points. In this position these wipers have completed the electrical connection between the calling station and the one wanted.

105 The subscriber now presses "2nd" key once closing connections for b² and E the same as before thus causing shaft N to be advanced one more step to bring wiper 114 into electrical connection with the magnet F. In this position the upper two wipers on the same shaft rest on the next to the last of their contact points, which contact points are in the talking circuit. This is the extreme position to which the magnet E can 110 advance the wipers on the shaft N, and the extreme position at which the holding pawl for the wheel N¹ can maintain them. The magnet F can, however, advance these wipers one more step when it is actuated, but 115 upon breaking the circuit through F the wipers fall back to the previously described extreme position.

The subscriber now presses "1st" key for 120 a period of time for ringing. This causes a current to flow as previously described for A² and B² except that this time it goes from 125 114 to 116 by the way of F. This advances temporarily the wipers on the shaft N, the last contact for wiper 114 being of extra 130.

length this advance does not break the connection for F.

While the wipers 126 and 141 are on their last contact points a current flows from the generator: G—123—124—125—126—127—128—129—130—136—135—134—20—T—4—133—132—131—137—138—139—140—141—142—143—144—G.

This signals the subscriber at the desired station and as soon as the calling subscriber breaks the circuit through F by releasing the "1st" key, the wipers 126 and 141 return to the contact points in the talking circuit. Beginning at the calling station this talking circuit is: T—20—85—84—83—42—43—44—45—46—122—121—90—91—92—93—94—141—140—139—138—137—131—132—133—4—T—20—134—135—136—130—129—128—127—126—145—105—106—107—108—109—20—110—111—66—67—68—69—70—71—72—73—4—T.

In the circuit T is an arbitrary for the telephone station at which there is presumed to be located the ordinary telephoning set including receiver, transmitter, induction coil, and battery arranged in the ordinary manner.

This talking circuit consists of two metallic connections between the two telephones, 30 in which connections there is no resistance other than that of the line itself. Between one of these line connections of the above circuit and the battery connections 1^a, 1^b, and 1^c there are bridged three magnets, b¹ 35 of the intermediate switch, b² of the auxiliary switch, and a of the called switch.

Between the other line and the same battery connections are also bridged three magnets, a, a¹ and a². These magnets are made 40 with equal resistances, and there being the same number on each branch the line is balanced.

When through talking the subscriber at the calling station presses both keys simultaneously but begins with the "1st" key a little in advance of the "2nd" key.

In calling devices of the kind usually used in automatic exchanges, operations of this kind are ordinarily performed automatically by a descent of the receiver hook when hanging up the receiver. The various circuits resulting from this permit impulses to pass, as will be described, for releasing the moved switches and permitting them to return to their normal positions. In this connection it is proper to note that the talking circuit just described has condensers in it, which condensers serve to stop a battery current and thus prevent the currents now to be described from going the wrong way.

Upon making the contacts just described a current flows: X—1—1^a—2—a—3—4—T—ground—X; also branch 1^b—64—a¹—65—66—67—68—69—70—71—72—73—4; also branch 1^c—103—a²—104—105—106—107—

108—109—110—111—66 etc. This circuit with its three branches through the relays a, a¹ and a² operates them and causes their respective armatures to make connections to the adjacent contact springs.

A current then flows: X—1—1^a—2—5—146—18—b—19—20—T—ground—X; also branch 1^b—52—82—49—48—b¹—47—46—45—44—43—42—83—84—85—20; also branch 1^c—99—112—113—97—96—b²—95—

94—93—92—91—90—121—122—46—etc. This circuit with its three branches through the relays b, b¹, and b² operates them and causes their respective armatures to make connections with the adjacent contact springs.

The operation of the relay a closed the circuit just described for b, and upon the operation of b a current flows: X—1—1^a—21—22—23—147—148—J—149—150—10—11—12^a—12—13—X.

The operation of the relays a¹ and b¹ close the circuit for the magnet J¹ of the intermediate switch when the current flows: X—1—1^b—52—53—54—151—152—J¹—79—80—81—63—12^b—12—13—X.

The operation of the relay b² closes the circuit for the magnet E when a current flows: X—1—1^c—99—100—101—102—E—98—12^c—12—13—X. Then the operation of a² and E close the circuit for the magnet J² when a current flows: X—1—1^c—99—112—153—154—155—J²—156—157—118—119—98—12^c—12—13—X.

The magnets J, J¹ and J² are the magnets used for releasing their several switches from their propelling magnets, which release may be mechanically effected in any of the well known ways.

For practical reasons relating to the times of breaking circuits the actual release does not occur upon the actuation of the release magnets, but upon the return of their respective armatures to their normal positions. Upon each release the switches fall back to their normal positions either under the force of gravity or the force of springs.

In the main switch some convenient part in returning to normal position strikes the rear end of the catch c and releases said catch from the spring 30, thereby permitting the other adjacent springs to resume their normal positions. Another part separates the springs 32 and 33. The same operations are performed in the same way by the

return movement of the intermediate switch, and in addition thereto the carriage moves lever 49 from contact point 82 to contact point 50. The auxiliary switch releases the holding pawl for the ratchet wheel N¹ and a catch associated with magnet L, provided that magnet has been operated as will be hereinafter described.

Returning now to the automatic upward movement of the main switch it will be re-

70

membered that this upward movement continued until the wipers carried thereby come into connection with an idle intermediate switch, when the main switch stops. In 5 case the wipers should pass over the entire vertical row of contact points without finding any idle intermediate switch then the wipers will pass over the strips 165 and 166 and wiper 43 will make a temporary connection with strip 158. Then a current flows: 10 X—1—1^a—21—38—39—40—C—41—42—43—158—159—12—13—X. This operates the magnet C and shifts the electrical connections of the adjacent springs as previously described.

As soon as this operation has been completed the upwardly moving carriage falls back with its wipers on the strips 165 and 166. This termination of the upward movement and the falling back of the carriage may be accomplished by terminating the ratchet upon which the magnet B operates to cause the upward movement, or by any other convenient means. In the drawings 20 it is shown as the direct result of operating the magnet C which breaks the circuit for B at the spring 30.

As soon as the wipers assume the position described a current flows: W—160—161—30 162—163—164—165—69—70—71—72—73—4—T—20—85—84—83—42—43—166—167—168—169—170—171—W. This throws a "busy buzz" back to the calling telephone whereupon the calling subscriber releases 35 his switch as previously described.

The intermediate switches are provided with the same kind of strips connected in the same way to the buzzer, and the consequence is that in case the main switch finds 40 an idle intermediate switch but the intermediate fails to find an idle auxiliary switch, then a busy buzz is sent back in the same way to the calling station.

In the case of the auxiliary switches the 45 system of sending back a busy signal is different. In this case each auxiliary switch is provided with an extra wiper and a corresponding group of contact points. It also has a magnet L for closing connections to the buzzer W. This difference arises from 50 the fact that in the first two cases the busy signal is sent back because an idle switch is not found, while in the third case the busy signal is sent back because two different subscribers have moved two different auxiliary switches to electrical connection with the main switch of some one subscriber.

For two auxiliary switches to move to 60 connection with the same main switch, both auxiliary switches must have their wipers in corresponding positions, and both must belong to the same primary group.

Assuming that both of the auxiliary switches of Fig. 3 had moved to electrical

connection to the switch of station No. 2,112, 65 then a current will flow: X—1—1^a—99—112—L—172—173—174—175—176—177—178—177 of the other auxiliary switch—176—175—174—98—12^a—12—13—X. This is on the assumption that the auxiliary 70 switch at the right of Fig. 3 was first in connection with the desired station and that the one at the left is the one moving to a connection already established. The circuit just described is not completed simply by 75 virtue of the second auxiliary switch moving to a previously established connection, but is completed only when the subscriber having stopped his auxiliary switch at an interfering connection closes the connection 80 for the magnet E to move the wipers on the shaft N to their extreme position.

The magnet L is provided with suitable connections of any of the well known kinds for releasing the pawls operating upon the ratchet wheel N¹. The operation of the magnet L caused by closing the circuit last described therefore causes a release of the shaft N from its propelling and holding devices and permits said shaft and the wipers 85 thereon to return to normal position. Attracting the armature of the magnet L by reason of this current closes 181 to 182 and 184 to 185. A hook adjacent to the armature holds these connections closed after 90 the circuit through L is broken, and until the carriage of the auxiliary switch is released and returns to its normal position.

While these contacts remain closed a current flows: W—160—179—180—181—182—100 105—106—107—108—109—110—111—66—67—68—69—70—71—72—73—4—T—20—85—84—83—42—43—44—45—46—122—121—90—91—92—93—94—183—184—185—186—187—171—W. This throws a buzzing 105 signal back into the calling telephone and indicates that the desired party is busy.

The case just described assumes that the subscriber at station No. 2,112 had been 110 called by some third party, and hence that the switch of the called station was at its normal position.

In case the subscriber at the desired station had called and was talking to some 115 third party, then his switch would be away from its normal position and the springs 132 and 135 would be moved away from contact points 133 and 134, and into connection with contact points 188 and 189. As the contact points 133 and 134 are in the 120 talking circuit of a called station telephonic connections cannot be made to a switch that has moved, and as the contact points 188 and 189 are connected by wires 190 and 191 to the previously mentioned buzzer circuit 125 an attempt to connect to a moved switch sends a busy signal back to the calling station.

Reviewing briefly what has been heretofore said it will be seen that the subscriber makes at his station, numbers of contacts that are indicated to him by the number of 5 the station he wishes to call. Also that after making the contacts for any number he makes one additional contact that sends an impulse over a line different from that which carried the impulses representing figures in the number for the desired station.

Ordinarily this extra contact is made automatically by the calling device used, a convenient one of which is shown in my Patent No. 822,965, issued June 12, 1906.

15 The switching mechanisms are operated from a battery by connections closed by keys at the station or by a suitable calling device. Each switch carries two insulated wipers which it first moves in one direction 20 and then in a direction perpendicular thereto, and passes over contact points which are connected to other switching mechanisms. These other switching mechanisms have a connection to the battery when they are in 25 their normal positions, but when a switch moves its normal connection to the battery is broken and a new one, through another line, is substituted therefor.

The insulated wipers just referred to are 30 not normally connected to the battery, but one of them has such a connection temporarily made at each forward movement over its contact points. This temporary connection and the normal connections of the 35 switches (those connected to these contact points) to the battery are such that when this wiper touches a contact point whose switch is in normal position, an impulse flows through that switch and this wiper 40 and causes that particular switch to be moved from its normal position. As the new connection to the battery of the switch thus automatically moved does not involve the same branch to the battery through 45 which the temporary circuit was made the switch is no longer in the same kind of an operative connection to this contact point.

It will be observed that the current which 50 flows through the wiper to cause an automatic selection of a switch which is at the time in its normal position emanates from the same battery which supplies the energy for moving the wipers.

In this automatic selection of an idle 55 switch it has been heretofore necessary to use an extra or auxiliary battery to furnish the necessary energy. This is because, in the circuits as heretofore arranged, combinations of movements of different switches 60 would sometimes send impulses which would disarrange the desired system of movements. By the present arrangement this does not occur and I am consequently enabled to dispose of the extra battery and the necessary connections therefor.

It will be observed that the wipers of a switch are not normally connected to the station, nor are they connected to the station during the time they are being moved. They are, however, both automatically connected to the station the instant that an idle switch is found by their movement. This connection is established by the operation of the magnet C, which magnet also stops the automatic movement of the switch. It will 70 be noticed from this that this automatic connection of the wipers to the station is in reality an extension of the line from the station, and that a part of this extension (the wiper 43) is used to form the temporary circuit for finding an unemployed switch. Upon the completion of this extension the newly selected switch bears the same relationship to the calling station that the originally moved switch bore at the time 75 of its movement. The line simply extends from the station through the first switch to the second switch.

Although the wires 4 and 20 which extend from the station do not normally connect to the wipers, yet the wipers when at normal position connect these wires to the springs 132 and 135, and these springs are in turn connected by wires 131 and 136 to some particular pair of wires in the bank of wires 90 to which the members of some group of auxiliary switches connect. These wires 131 and 136 are really extensions of the bank wires and may be called normal wires of a station because, when the main switch of a station is at its normal position, these wires are connected directly to the station. As soon as the main switch moves away from its normal position its normal wires are automatically connected to the busy signaling 95 device W by means of the wires 190 and 191 as will be most readily seen by inspecting the right hand portion of Fig. 1. As a consequence of this, when some subscriber has selected an auxiliary switch in the manner previously described and has moved that auxiliary switch to the normal wires of some other station, he either connects to that station or to the busy signal according to 100 whether the switch of that station is at its normal position or has been moved.

By referring back to the main switch of a calling station, it will be noticed that the wipers are not connected to the lines running to the station until the switch movements have been stopped. If this stoppage occurs before the switch reaches its extreme position the connection of the station is to some other switch, but if the stoppage is only at the extreme position, then the connections intended for a talking circuit extend directly to the busy signaling device W.

In the same way, when an intermediate switch has been selected and moved, the extended connections of the stations either 130

connect to some auxiliary switch or directly to the same busy signaling device. And again, when the auxiliary switch is similarly moved the still further extended connections of the station connect to the normal wires of some other station and either reach that station or directly to the same busy signaling device.

It will be seen that in all of these operations the busy signaling device is connected directly to the lines intended for a talking circuit, and that no third wiper is required to accomplish the desired result. The only time that a third wiper is used is in that combination in which two auxiliary switches connect to the same pair of normal wires.

In applications previously filed by me, as in my Patent No. 747,197, issued Dec. 15, 1903, and in my Patent No. 1,369,288, issued Feb. 22, 1921, interfering connections were prevented by breaking the line intended for a talking circuit thus leaving the calling station with open connections. In the present case interference is not accomplished by breaking the connections used or intended for a talking circuit but by shifting those connections directly to a busy signal device.

What I claim is:—

1. In a telephone exchange having a main switch for each station belonging to the exchange, a division of such main switches into primary groups containing a number of switches and into secondary groups each consisting of a number of primary groups, a separate bank of wires for each secondary group of main switches, contact points on each main switch connected to the different wires of the bank of wires to which it belongs, a set of auxiliary switches less in number than the main switches and correspondingly divided into primary and secondary groups, a bank of wires connecting contact points on the auxiliary switches of each primary group with the different switches in corresponding primary group of main switches, and a set of intermediate switches correspondingly divided into primary and secondary groups and provided with banks of wires and connections by which telephonic connections may be extended from any main switch in any primary group to some auxiliary switch in some different primary group.
2. A set of main switches divided into primary and secondary groups, lesser sets of intermediate and auxiliary switches each of which is similarly divided into primary and secondary groups, electrical conductors from each main switch of each secondary group to all of the intermediate switches in a plurality of the primary groups of intermediate switches, other electrical conductors from each primary group of intermediate switches to all of the auxiliary

switches in a plurality of groups of auxiliary switches, and return conductors from each auxiliary switch of each primary group to all of the main switches located in a corresponding primary group of main switches.

3. In a telephone exchange, a plurality of sets of switches, a division of each set of switches into primary and secondary groups, and electrical connections so arranged that all of the individual switches of a secondary group of one set have the same electrical connections to some one primary group of each secondary group into which the next successive set of switches is divided.

4. In a telephone exchange, the combination with a set of main switches divided into primary and secondary groups, a lesser set of intermediate switches divided into corresponding lesser primary and secondary groups, and a set of final switches corresponding in number and groupings to the intermediate switches, of connections from each primary group of main switches to a plurality of secondary groups of intermediate switches not in the same primary group, similar connections from each primary group of intermediate switches to a plurality of secondary groups of final switches not in the same primary group, and other connections from each secondary group of final switches to the corresponding secondary group of main switches.

5. A switching mechanism provided with a pair of wipers through which a talking circuit is to be completed and said wipers adapted to be moved successively to the electrical connections of different switches of a group of switches, a group of such switches, a telephone station provided with normally open connections to the wipers being moved, a magnet by the operation of which upon reaching connection to an idle switch in said group of switches said wipers will be automatically stopped and their normally open connections to said station will be closed, and means by which the circuit for said magnet is completed by one of said wipers.

6. A group of switches each of which is provided with a pair of electrical connections, a pair of wipers adapted to be moved successively to the electrical connections of said switches, devices for so moving them, a telephone station provided with a pair of electrical connections, and means operating through one of said wipers by which upon the said wipers reaching connection to an idle one of said switches the pair of connections belonging to said station will be automatically connected to said wipers.

7. A group of switches each of which is provided with electrical connections, a pair of normally disconnected wipers and means for moving them successively to the electri-

cal connections of said switches, a telephone station, and means operating through one of said wipers by which upon said wipers reaching connection to an idle one of said switches further movement of said wipers will be automatically stopped and said wipers will be automatically placed in electrical connection with said station.

8. A telephone station, a pair of wipers therefor located at a central office and normally disconnected from the station, means by which said wipers may be moved so that they will be automatically associated with an idle switch, a group of switches out of

15 which such idle one is selected, and means operating through one of said wipers by which said wipers will be automatically connected to said station upon the association of said wipers with an idle switch.

20 9. In a telephone exchange, the combination with a pair of wipers, a telephone station and a group of switches, of means for moving said wipers to make successive electrical connections with the switches of said

25 group, and means operating through one of said wipers by which electrical connection is automatically established between said wipers and said station, when said wipers reach connection to a switch in said group which

30 is at the time in its normal position.

10. In a telephone exchange provided with successive sets of switches each set of which is divided into groups, a pair of wipers on each switch serving as part of any 35 talking circuit established by said switch, means by which upon moving the wipers on a switch of the first set to electrical connection with a group of the switches in the next successive or second set, an electrical impulse will flow through one of said wipers to cause an automatic association of the moved wipers with an idle switch in said group of switches, and means by which upon moving the wipers of the switch thus automatically selected to electrical connection

45 with a group in the next successive or third set a similar impulse through one of the moved wipers will cause a similar association between the moved wipers of the 50 switch of the second set and an idle one of the switches in the third set.

11. The combination with a pair of wipers, a telephone station and a series of groups of switches, of means by which said 55 wipers may be moved to successive switches of any group of switches, and means operating through one of said wipers by which upon said wipers reaching connection to a switch that is at the time in normal position such switch will be automatically placed in electrical connection with said station.

12. The combination with a switching mechanism provided with a pair of wipers, a telephone station in electrical connection 60 with said switching mechanism but not with

the wipers thereof, and a group of other switching mechanisms, of means by which the first mentioned switching mechanism may be operated so as to move its wipers successively to electrical connections belonging to members of said group, and means by which upon said wipers reaching the connections of a member which is at the time in its normal position the electrical connections from said station will be automatically extended to such member of the group of switching mechanisms and the member will be automatically moved from its normal position.

13. The combination with a series of switches, and means for automatically selecting an idle one of said switches, of a battery provided with a normal connection to each switch while in its idle condition, means by which the normal connection to a switch is broken at the time it is selected, and means by which a new connection of a different kind is made between the battery and the switch upon the completion of its selection.

14. A battery, a switching mechanism having its operating devices connected to one side of the battery, a telephone station provided with means for connecting the operating devices to the other side of the battery so as to cause an operation of the switching mechanism, a wiper moved by each operation of said switching mechanism and normally disconnected from said battery, means by which said wiper is temporarily connected to said battery at the time of each movement, a series of contact points in the path of such movement of said wiper, a different switching mechanism connected to each contact point, and other connections from said battery to each of the different switching mechanisms, said other connections being each so arranged as to be closed when its switching mechanism is at its normal position and to be open when its switching mechanism has been moved away from its normal position.

15. A battery, a switching mechanism adapted to be operated by impulses sent from said battery, a wiper moved by each operation, means by which said wiper is temporarily connected to said battery at time of each movement, a series of other switching mechanisms each having an electric terminal at a different position in the path of said wiper, and other connections from the battery to the other switching mechanisms each so arranged as to be closed when its switching mechanism is at its normal position and to be open when its switching mechanism has been moved.

16. A battery, a switching mechanism adapted to be operated by impulses sent therefrom, a wiper moved by each operation, means by which said wiper is tempo-

rarily connected to said battery at time of being moved, a magnet in the connection between said wiper and the point at which it is connected to said battery, a series of other switching mechanisms each provided with an electric terminal at a different point in the path of said wiper, and a normally closed connection from said battery to each of the other switching mechanisms, which connection is broken when the switching mechanism is moved.

17. The combination with a telephone station, a switching mechanism connected to said station, and a battery having one side connected to said switching mechanism and the other side connected to said station whereby said switching mechanism may be operated from said station, of a pair of wipers moved by each operation of said switching mechanism, and normally disconnected from both said station and said battery, pairs of contact points in the paths of said wipers, a different switching mechanism connected to each pair of contact points, a connection from each of the different switching mechanisms back to said battery, which connection is closed when the switching mechanism is at its normal position and is open when said switching mechanism is moved, means by which one of said wipers will be temporarily connected to said battery at each of its movements, and means whereby upon such a connection being made for said wiper at a time when the wiper reaches a contact point belonging to one of the other switching mechanisms which has its normal connection to the battery closed both of said wipers will be automatically connected to said station and the operating parts of the first mentioned switching mechanism will be automatically disconnected from said battery.

18. The combination with a series of sets of switching mechanisms, and a busy signal device, of means by which a switch in the first set may be moved so as to automatically make connections to some idle switch forming a part of the second set, means by which the switch so selected may be operated so as to be automatically connected to some idle switch in the third set, connections from the busy signal device to all of the switches, and means by which upon any switch failing to connect to some idle switch of the next set when operated the switch failing to make such connection will be automatically connected to said busy signal device.

19. The combination with a station, a switching mechanism connected to said station, and a pair of wipers moved by said switching mechanism but disconnected from said station, of a magnet for connecting the wipers to the station, and means by which upon operating said switching mechanism one of said wipers completes a temporary

circuit for said magnet to operate it and cause said wipers to be connected to said station.

20. The combination with a station, a switching mechanism connected to and operated from said station, and a pair of wipers moved by said switching mechanism but disconnected from said station, of a normally inactive magnet arranged upon operation to cause the connection of said wipers to said station, and means by which upon operating said switching mechanism one of said wipers completes a temporary circuit for said magnet.

21. The combination of a battery, and a series of switches each provided with a connection to one of the poles of said battery, of means for automatically selecting an idle one of said switches, and means by which upon making such selection the selected switch has its connection shifted to the opposite pole of said battery.

22. The combination with a station, a switching mechanism adapted to be moved from a normal position, and a busy signaling device, of a pair of connections from the station to the switching mechanism, a second pair of connections between the busy signaling device and the switching mechanism, a third pair of connections called normal wires from the switching mechanism to a bank of wires, means by which the first and third pairs of connections are in electrical connection with each other when the switching mechanism is at its normal position, and means by which the electrical connection of the third pair of connections is automatically shifted from the first pair to the second pair when the switching mechanism is moved from its normal position.

23. The combination with a station, a switching mechanism adapted to be moved from a normal position, and a busy signaling device, of a pair of normal wires in electrical connection with said station when said switching mechanism is in its normal position, and means by which the electrical connections of said wires are automatically shifted from said station to said busy signaling device upon the movement of said switching mechanism from its normal position.

24. The combination with a telephone station provided with a pair of electrical connections, and means by which said connections are extended through successive stages to form a talking circuit to some other station, of a busy signalling device, and means by which upon any failure to extend said connections at any stage said connections will be automatically connected direct to said busy signaling device.

25. The combination with a telephone station provided with a pair of electrical connections, and means by which said con-

nections are extended through successive stages to form a talking circuit to some other station, of a busy signaling device provided with connections extending to points adjacent to where each of said stages is completed, and means by which upon a failure to complete the desired extension at any stage the connections being extended will be automatically connected to the adjacent connections of the busy signaling device.

26. The combination with a switching mechanism, a battery provided with connections by which said switching mechanism is moved, and a wiper carried by such movement, of a series of branches from said connections having terminals in the path of said wiper, a different switching mechanism in each branch, and means by which upon said wiper making connection to the terminal of a branch which included a switching mechanism in its normal position a current will flow from said battery through that branch and cause its switching mechanism to be moved away from its normal position.

27. The combination with a switching mechanism and a battery provided with connections for moving it, of a series of other switching mechanisms, branches from the connections to said battery and including said other switching mechanisms and means by which upon operating the first mentioned switching mechanism a current will flow through one of said branches and cause a movement of the switching mechanism included therein.

28. The combination with a vertically and transversely movable carriage, and means for moving it in both of said directions, of a contact closed by said carriage upon making its first movement in one of said directions, and means by which an impulse sent through said contact serves to start said carriage into an automatic continuous movement in the other direction which movement breaks said contact.

29. The combination with a movable carriage, and separate devices for moving it laterally and vertically any desired number of steps, of an electrical contact closed for the vertical movement of the carriage when said carriage is moved one step laterally, said contact being held closed during any further lateral steps, means by which said contact is broken when the carriage moves upward one step, and automatically operating means for continuing the upward movement of the carriage after said contact is broken.

30. The combination with a vertically movable carriage, and automatically operating means for causing it to move upward step by step, of a transversely movable carriage, devices for so moving it, a contact with which the transversely movable car-

riage closes electrical connection when moved one step, which electrical connection is broken by the upward movement of the vertically movable carriage, and means for starting the vertically movable carriage into automatic operation by an impulse sent through said contact.

31. The combination with a telephone station, a series of trunk lines, and a pair of contact makers normally disconnected from both the station and the trunk lines, of means controlled from the station for starting the contact makers into automatic operation to make connections successively to said trunk lines, a magnet for connecting the contact makers to the station, and means by which upon the contact makers finding a non-busy trunk line an impulse will flow through said magnet and over the found trunk line so as to cause the actuation of said magnet and the connection of the station to the trunk line.

32. The combination with a telephone station, a pair of wires leading from the station to a central office, and a pair of wipers located at the central office and normally disconnected from said wires, of a series of trunk connections, magnets operable by impulses sent over said wires to bring about a movement of said wipers to select a non-busy trunk connection, and means by which upon said wipers finding a non-busy trunk connection non-inductive connections will be automatically completed from said station to said wipers.

33. The combination with a telephone station, a pair of wires leading from the station to a central office, and a pair of wipers at the central office and normally disconnected from said wires, of a series of trunk lines, means for moving said wipers so as to select a non-busy trunk line, and means by which upon said wipers finding a non-busy trunk line non-inductive connections will be automatically completed between said station and said wipers.

34. The combination with a telephone station, a pair of wires leading from the station to a central office, and a pair of wipers at the central office and normally disconnected from said wires, of a series of trunk lines, means for moving said wipers so as to select a non-busy trunk line, a magnet for connecting said wires to said wipers, and means for operating said magnet by an impulse flowing over the found trunk connection.

35. A battery, a switching mechanism arranged to be moved step by step by impulses sent from said battery, a pair of wipers normally disconnected from said battery, and means by which one of said wipers is temporarily connected to said battery at the time of each forward step of said mechanism.

36. A switching mechanism adapted to be

12 moved to select an idle trunk, a battery furnishing the motive force for such movement, a trunk-selecting wiper carried by said mechanism and normally disconnected from 15 said battery, means by which said wiper is temporarily connected to said battery at each movement of said mechanism, and means by which an impulse from said battery through said wiper serves to cause the 20 selection of the idle trunk.

125 37. In a telephone exchange provided with main switches, intermediate switches and auxiliary switches, a pair of wipers on each switch, a station connected to each main switch, a pair of normally disconnected conductors from the wipers of each intermediate switch to contact points on a plurality of main switches, a similar pair of normally disconnected conductors from the wipers of 20 each auxiliary switch to contact points on a plurality of intermediate switches, a pair of connected conductors from the connections of each station to contact points on a plurality of auxiliary switches, and means by which upon operating a switch of each kind the connected conductors become disconnected conductors and the disconnected conductors become connected conductors.

30 38. The combination with successive series of switches, connected and disconnected conductors between the series, and means by which upon operating one switch of each series a telephonic connection is established between points on two switches of the same 35 series, of means by which the establishment of such telephonic connection is by means of changing normally disconnected conductors into connected conductors and normally connected conductors into disconnected conductors.

40 39. The combination with successive series of switches, connected and disconnected conductors between the series, and means by which upon operating one switch of each series a metallic circuit is completed between 45 points on two different switches in the first series, of means by which such operation changes normally disconnected conductors to connected conductors and normally connected conductors into disconnected conductors.

50 40. The combination with a series of telephone stations, a corresponding series of switches located in a central office and each switch connected to its corresponding station, a second series of switches less numerous than the first, and means controlled from each local station for operating its connected switch so as to automatically select an idle one of the second series of switches, of a 55 battery provided with a normal connection to each switch of the second series while in its idle condition, means by which the normal connection to such a switch is broken at the time it is selected, and means by which 60

65 a new connection of a different kind is made between the battery and the switch upon the completion of the selection of the second switch by the first.

41. In a telephone exchange, the combination of a calling telephone line, a called 70 telephone line, a connector for completing connection with the called line, trunk lines and a plurality of trunking switches for extending connection from the calling line to said connector, a trunk release circuit 75 extending through and including all of said automatic switches in parallel, and a battery for energizing said release circuit.

42. In a telephone exchange system, a plurality of selectors and a connector, each 80 provided with a release relay, a trunk release circuit including said relays in multiple, and a source of current connected to said circuit.

43. A telephone exchange system comprising 85 a subscriber's telephone line, an active switch contact in which said subscriber's line terminates, co-operating passive contacts adapted to be engaged by said active contact, a plurality of link-circuits extending 90 from said passive contacts, means for causing said active contact to automatically select and stop in engagement with the passive contact of an idle one of said link-circuits, and means for sending a characteristic 95 signal over said subscriber's telephone line in case all of said link-circuits are in use.

44. A telephone exchange system comprising 100 a subscriber's telephone line, an active switch contact in which said subscriber's line terminates, co-operating passive contacts adapted to be engaged by said active contact, a plurality of link-circuits extending 105 from said passive contacts, means for causing said active contact to automatically select and stop in engagement with the passive contact of an idle one of said link-circuits, means for sending a characteristic signal over said subscriber's telephone line in case all of said 110 link-circuits are in use, and means whereby the subscriber may then restore said active contact to normal.

45. A telephone exchange system comprising 115 a subscriber's telephone line, an active contact in which said subscriber's line terminates, co-operating passive contacts adapted to be engaged by said active contact, electrically operated signal transmitting apparatus associated with the last of said passive contacts to be engaged, a plurality of link-circuits extending from the remaining passive contacts, means for causing said active contact to pass over said passive contacts, means for arresting said movement 120 in case an idle passive contact is encountered, means for operating said signal transmitting apparatus in case its passive contact 125

is engaged by said active contact and signal receiving means associated with said telephone line.

46. A telephone exchange system comprising a subscriber's telephone line, a plurality of associated link-circuits, interconnecting switch mechanism comprising an active contact, co-operating passive contacts adapted to be engaged by said active contact, means for causing said active contact to pass over said passive contacts and means for arresting said movement in case an idle passive contact is encountered, electrically operated signalling apparatus associated with the last 15 of said passive contacts, and means for operating said signalling means as soon as its passive contact is engaged by said active contact.

47. A telephone system including telephone lines, interconnecting link circuits, a plurality of selective switch mechanisms for uniting a calling and a called line by link circuits into a talking circuit, a testing contact associated with one of said mechanisms 25 for selecting a link circuit to be included in said talking circuit, a circuit for releasing one of said switch mechanisms including said testing contact, and means for controlling said circuit.

48. A telephone exchange, lines extending from substations thereto, link circuits, switch mechanisms, a test contact associated with one of said mechanisms for selecting a link circuit to complete a talking circuit between a calling and a called line, and a circuit for releasing one of said mechanisms including 35 said test contact.

49. A telephone exchange, lines extending from substations thereto, link circuits, switch 40 mechanisms, a test contact associated with one of said mechanisms for selecting a link circuit to complete a talking circuit between a calling and a called line, a circuit for releasing one of said mechanisms including 45 said test contact, and means at said substations for controlling at will said releasing circuit.

50. A telephone exchange, lines extending from substations thereto, link circuits, switch 50 mechanisms, a test contact associated with one of said mechanisms for selecting a link circuit to complete a talking circuit between a calling and a called line, a circuit for releasing one of said mechanisms including 55 said test contact, said test contact being in the talking circuit.

51. In a telephone exchange system, provided with selector switches of various classes at the exchange, including connector 60 switches adapted to cooperate with calling devices at the substations in establishing desired connections, the combination with a subscriber's line, of a first selector switch adapted to be operated under substation

control, second selector switches, multiple 65 terminals of said second selector switches, and wipers included in said first selector switch adapted to engage said terminals, a part of said wipers being for conversational use, a test wiper enabling said first selector to select and isolate an idle second selector, means for causing a flow of current over said wiper when disconnection is desired, and release mechanism at the exchange operated responsive to said flow. 75

52. A telephone system including a pair of connected telephone lines, a plurality of selective switches at the exchange through which the conversational circuit extends, a multiple private or test contact for one of said switches for preventing intrusion upon the conversational circuit, and means for altering the electrical condition of said contact to restore to normal one of said switches. 80

53. A telephone system including a telephone line, a selective switch at the exchange connected with said line, a second selective switch connected with said first switch, contacts of said switches forming 90 part of a talking circuit, an additional contact piece for said first switch in connection with a contact of said second switch serving to protect the talking circuit from intrusion, means for altering the electrical condition of said contact piece when disconnection is desired, and release mechanism for restoring a selective switch responsive to said altered electrical condition. 95

54. A telephone system including telephone lines, interconnecting link-circuits, a plurality of selective switch mechanisms for uniting a calling and a called line by link-circuits into a talking circuit, a private contact associated with one of said switch mechanisms, a connection device for contact therewith to place a busy potential upon said contact to protect the talking circuit from intrusion, a release circuit for one of said switching mechanisms including said private contact, and apparatus for altering the potential of said private contact when disconnection is desired to render said release circuit effective. 100

55. The combination with a series of contact points representing idle and busy lines, a contact maker arranged so that when moved it will engage said contact points in succession, and a battery provided with an electrical connection to said contact maker, of a magnet provided with means controlled by its own operation for automatically advancing said contact maker over said contact points, a second magnet energized by impulses flowing from said battery through said contact points when the said contact maker engages a contact point representing an idle line, and means controlled by 110

said second magnet for interrupting the automatic advance of said contact maker.

56. The combination with a series of contact points representing idle and busy lines, 5 a contact maker adapted to be moved to said contact points in succession, and a battery, of a magnet for advancing said contact maker step-by-step, means associated with said magnet and controlled by the movements of its armature for maintaining it in 10 automatic operation upon the receipt of an initiatory impulse from said battery, and a second magnet energized through said contact maker upon engagement with a contact point which represents an idle line for automatically interrupting the automatic operation of the first magnet.

57. The combination with a series of contact points representing idle and busy lines, 20 and a contact maker adapted to be moved to said contact points in succession, of a magnet adapted to be operated successively to advance said contact maker step-by-step to successive contact points, means controlled through the operations of the magnet for maintaining it in operation when started, and a second magnet energized through said contact maker when said contact maker engages a contact point representing an idle line for interrupting the operation of the first magnet.

58. The combination with a switching device comprising a series of contact points representing idle and busy lines and a contact maker adapted to engage said contact points in succession, and a magnet for moving it, of an open contact device adapted to be closed upon the first movement of the switch from normal position, automatic means operating through said contact device for continuing the operations of said magnet, and a second magnet controlled through said contact maker for interrupting the operations of the first named magnet when said contact maker engages a contact point representing an idle line.

59. The combination with a switching device having a series of contact points representing idle and busy lines to which it is adapted to make connections successively, and a battery, of a magnet arranged to advance said switching device step-by-step by impulses from said battery, means controlled by the operation of the magnet for automatically continuing the impulses through said magnet, a second magnet for interrupting the impulses through the first magnet, said second magnet being provided with connections by which it may be controlled through a talking circuit contact on the switching device representing any one of said lines, and means by which such interrupting action takes place upon connection being made by the switching device

to the first contact point representing an idle line.

60. The combination with a switch provided with contact points representing idle and busy lines and a pair of wipers for engaging such contact points, electromagnetic devices for automatically advancing said wipers step-by-step over said contact points upon the receipt of an initiatory impulse, and a magnet provided with connections by which it may be energized when the wipers engage contact points representing idle lines and means operated by said magnet for interrupting the step-by-step motion of said switch, of a pair of subscribers' lines leading to said wipers but disconnected therefrom during the automatic advance of said wipers to find contact points representing an idle line, and automatic means for connecting said subscribers' lines to said wipers upon the stopping of said switch.

61. A subscriber's line, a switch provided with contact points representing idle and busy trunks and with wipers adapted to engage the contact points, means for automatically moving said wipers over the contact points of busy trunks while said wipers are disconnected from the subscriber's line, a battery, a magnet provided with connections to said battery and one of said wipers whereby, on said wiper finding a circuit, 95 said magnet will be operated and means by which the operation of said magnet will stop the movement of said wipers.

62. A subscriber's line, a pair of movable wipers for connection thereto but normally disconnected from said line, a series of contact points in the path of each wiper, said contact points representing idle and busy trunks, means for automatically moving said wipers into engagement with the contact points, and means operated by the engagement of one of said wipers with a contact point representing an idle trunk for stopping the movement of said wipers.

63. A subscriber's line, a pair of movable wipers normally disconnected therefrom, a series of contact points in the path of each wiper, said contact points representing busy and idle lines, means for automatically moving said wipers over said contact points, and means actuated through the engagement of one of said wipers with a contact point representing an idle line for stopping the movement of said wipers and simultaneously connecting said wipers to 120 said subscriber's line.

64. A switch provided with contact makers adapted to make contact in succession with contact points representing idle and busy trunks, a magnet and devices associated therewith for automatically advancing said switch step-by-step upon the reception of an initiatory electrical impulse,

a pair of subscriber's lines terminating in disconnected contact springs, other adjacent contact springs provided with connections to said magnet and said wipers, and a second magnet controlled through one of said wipers and a contact point representing an idle line for shifting the last named contact

springs so as to interrupt the operation of the first named magnet and to extend the connections of the subscriber's lines to said 10 wipers.

Signed at Chicago, Ill., this 19th day of July 1904.

FRANK A. LUNDQUIST.
